[57] CLAIM

The ornamental design for a combined bottle and cap, as shown and described.

DESCRIPTION

FIG. 1 is a front elevational view of a combined bottle and cap showing my new design;

FIG. 2 is a side elevational view thereof, the opposite side elevational view being a mirror image thereof;

FIG. 3 is a rear elevational view thereof;

FIG. 4 is a top view thereof;

FIG. 5 is a bottom view thereof;

FIG. 6 is a top front perspective view thereof;

FIG. 7 is a top right front perspective view thereof;

FIG. 8 is a front elevational view showing my new design without the cap;

FIG. 9 is a side elevational view thereof, the opposite side elevational view being a mirror image thereof;

FIG. 10 is a rear elevational view thereof;

FIG. 11 is a top view thereof;

FIG. 12 is a top front perspective view thereof; and,

FIG. 13 is a top right front perspective view thereof.

The bottle is shown without the cap in FIGS. 8 through 13 for clarity of illustration.
